UNITED STATES PATENT OFFICE.

GEORGE W. NELSON, OF CLEVELAND, OHIO, ASSIGNOR TO THE STANDARD SEWING MACHINE COMPANY, OF CLEVELAND, OHIO, A CORPORATION OF OHIO:

MACHINE FOR SEWING ON BUTTONS OR FASTENERS.

Application filed May 7, 1923. Serial No. 637,232.

The invention relates to sewing machines of the class adapted for sewing snap fasteners or buttons to garments, and which comprises a work-holder and means for operating said work-holder to present the several eyes of a supported fastener or button to the stitching mechanism.

In a machine of this kind, it is important that the eyes of the fasteners or buttons be accurately presented to the needle for the proper passage of the latter therethrough in the stitching operation, and it has therefore been one of the objects of the present invention to provide an improved operating mechanism for the work-holder which will be effective to such end. In accomplishing this, I provide an operating mechanism including two members, one, such as a ratchet having connection with the work-holder, and the other, such as a pawl being operative to engage said ratchet and impart an intermittent movement to the same and associated work-holder; and in connection with such parts, I employ means for causing the ratchet member, and thereby the connected work-holder, to stop in a predetermined position following each movement imparted thereto by the actuating pawl member, which predetermined position of the work-holder is one with the eye of the supported fastener or button directly in the path of the sewing machine needle.

A further desideratum in a machine of the present type is the securing of the last sewing stitch of a group by a series of so-called "tacking" stitches, which latter are usually taken in the last eye of the fastener or a button, entered by the needle, to permit which the work-holder is caused to remain stationary. It has therefore been a further object of the invention to provide a simple and efficient tacking means for co-operation with my improved work-holder operating mechanism.

Other objects and advantages will appear in the detailed description of the invention which follows.

Referring now to the accompanying drawings in which I have shown only so much of a sewing machine as is necessary to illustrate my invention,—

Figure 1 is a plan view of the bed of a sewing machine having supported thereon the work-holder and its operating mecha-

nism, the usual overhanging arm and supported needle mechanism being omitted.

Fig. 2 is a sectional elevation of the same, the section being taken on line 2—2 of Fig. 1.

Fig. 3 is a detail, in top plan, showing by full and dotted lines the operation of the tacking device.

Fig. 4 is a section on line 4—4 of Fig. 3.

Fig. 5 is a view in side elevation of certain of the parts shown in Fig. 4, in disassembled relation.

Figs. 6 to 10 inclusive are top plan views of the parts shown in Fig. 5, other than the two lower screws.

Fig. 11 is a plan view of one of the parts of the tacking device.

Similar reference characters indicate like parts in the several figures of the drawings.

The frame base or bed of the machine here shown comprises a hollow standard 1 adapted to rest and be secured on a suitable supporting table, and having the usual horn extension 2 at the sewing end of the machine for the convenient manipulation of the work in presenting the same to the stitching mechanism.

Suitably journaled in this bed is the usual drive shaft 3 having an operative connection at its front end with the hook (not shown) of the stitching mechanism, and at its rear end being adapted to extend beyond the base 1 for connection with a suitable stop mechanism, such, for example, as that shown in Letters Patent No. 1,252,931, issued January 8, 1918, which is operative to stop the machine upon completion of each group of stitches made in the sewing on of individual fasteners or buttons.

Mounted upon the upper surface of the bed plate is a work-holder, indicated generally by *w*, which may be of any suitable or desired construction to hold a fastener or button in sewing relation to the garment or other work to which it is to be attached. This work-holder is slidably held on the bed plate by means of a headed pin or screw 4 on said plate engaging the base plate 5 of the work-holder in a longitudinal slot 6 therein, which connection permits of combined longitudinal and oscillating movements of the work-holder whereby it may be operated to move a fastener or button supported at its front end in a path to present

the successive eyes of the fastener or button to the stitching mechanism so that the connecting stitches will form a square or polygon, as shown in Fig. 1. This method of laying the stitches about the center of the buttons or fasteners renders the machine especially suitable for use in sewing on snap fasteners, in which the connecting ball and socket members of the same are centrally located and would therefore be within the space outlined by the connecting stitches, as shown in Fig. 1, which illustrates at *f* one of the members of a snap fastener held by the work-holder.

15 The means for operating the work-holder in the manner described comprises a rotatable ratchet member 10 suitably mounted on the bed-plate of the machine and having at its upper side a crank pin 11 pivotally connecting with a plate 12 which is rigidly attached to the rear end of the base plate 5 of the work-holder and constitutes an extension of the latter. Intermittent rotary movement of this ratchet member 10 will 20 operate the connected work-holder to impart a similar movement to its front end and thereby cause the latter to successively present the eyes of the supported fastener to the needle, the intermission between the successive movements being timed to permit of the necessary stitch-forming operation in each successive eye.

25 The diameter of the path of movement of the front end of the work-holder in presenting the eyes of a supported fastener to the needle will be determined by the diameter of the circle described by the actuating crank pin 11 on the ratchet member 10, and in order that the diameter of the said path of 30 movement may be varied to meet the requirements of different sizes of fasteners, the said crank pin is adjustable radially of the ratchet member whereby to vary the diameter of its path of movement and thereby 35 of that of the front end of the connected work-holder. Such adjustment of the crank pin is effected by mounting the same on a block 14 which is slidably supported in a transverse groove 15 in the upper side of 40 the ratchet member and adjusted therein by means of a screw 16 which is threaded into the block and held against longitudinal movement by a notched cap 17 fitted over the upper grooved end of the ratchet member and engaging within an annular groove 18 in the head of the screw. With this arrangement of parts, a turning of the screw 16 in the proper direction will operate to move the block 14 back and forth in the groove 15 and so give the desired adjustment 45 of the crank pin 11.

60 The ratchet member is intermittently operated in the manner described by means of a pawl 20 pivotally mounted on an oscillatory carrier 21, here shown in the form of

a ring mounted on the bed plate concentric with the ratchet for the engagement of its supported pawl with said ratchet. This pawl carrier is operated from a grooved cam 23 on the drive shaft through a lever 24 and connecting rod 25, the said lever being pivoted on the bed plate at 26 and having a roller stud 27 at its under side engaging the cam through an opening in the bed plate, and the rod 25 connecting at one 70 end with the free end of said lever and at its opposite end with the pawl carrier at 29. With this actuating means, constructed and adjusted in the manner shown, the pawl 20 is operated to give the ratchet four intermittent quarter turns in effecting a complete rotation of the same, which movements of the ratchet operates the connected work-holder to successively present to the needle the four eyes of a supported fastener. 80

As hereinbefore referred to, it is important that the eyes of the fastener or button be accurately presented to the needle for the free passage of the latter therethrough in the sewing operation. To effect this, I have provided the ratchet member with a plurality of open seats or depressions 30 in its under side, here shown as four in number, which are engaged by yieldable devices, here shown in the form of balls 31 resting on the top of 90 coiled springs 32 carried in a stationary support. These balls will readily yield to permit of the ratchet disc being rotated under the action of the driving pawl, but will snap back into the succeeding seats when the 100 ratchet has been given its predetermined movement and bring the same and connected work-holder to a stop in predetermined position upon each actuation thereof.

105 The pawl and ratchet devices, together with the several directly associated parts, may be supported and arranged in any suitable way, although I prefer to combine them in the manner here illustrated. In doing this, I employ a base plate 35 which is adapted to be secured in a stationary position on the bed plate by suitable fastening screws. This base plate is formed with a central opening and provided at its under side with a tubular extension 37 coincident with its 110 said opening. On the upper side of the base plate is a raised hub portion 38 on which rests the annular pawl carrier 21. Resting in turn on this pawl carrier is the ratchet member 10 which is provided at its under side with a cylindrical extension 39 which extends downward through the openings of the pawl carrier and base plate into the tubular extension 37 at the under side of the latter, in which it fits as shown. 115

120 The ratchet positioning balls 31 and their supporting and operating springs 32 are seated within pockets 40 in the base plate for upward pressure against the under side of the ratchet. As a means for holding the 130

latter in its normal vertical position and against the pressure of said balls, I have threaded a screw 41 into the lower end of the ratchet extension 39 with its head overlapping the end of the base plate extension, as shown in Fig. 4. A set-screw 42 threaded into this holding screw 41 with its inner end projecting into engagement with the ratchet extension, serves to lock the screw 41 in its adjusted position. Fitted over the upper slotted end of the ratchet member, thus held to the base plate by the screw 41, is the cap 17, which is adapted to be fastened in position to retain the crank-pin carrying block 15 within the transverse groove of the ratchet member, by fastening screws 43.

After the work-holder has been operated to present the fastener to the stitching mechanism for a predetermined number of sewing-on stitches and just prior to the making of the last few stitches of a group or series before stopping of the machine by the automatic stop mechanism, the feeding movement of the work-holder is adapted to be automatically stopped with the last eye of the fastener in the path of the needle so that the last few stitches of the group or series may serve as fastening or tacking stitches. The means for doing this comprises an oscillatory ring 45 mounted on the base plate 35 for movement about the hub portion 38 and having a pin or projection 46 adapted for movement from an inoperative position out of the path of the heel 47 of the pawl 20, as shown by full lines in Fig. 3, to an operative position in the path of said heel, as shown by dotted lines in said figure, in which operative position it acts to prevent the toe of the pawl engaging the teeth of the ratchet member to operate the latter and connected work-holder. This of course results in the work-holder remaining stationary for the sewing of the tacking stitches.

The operation of the ring 45 with its pin 46 is controlled from a cam 50 mounted on a transversely arranged shaft 51 driven from the main shaft 1 through worm-gearing 52, shown by dotted lines in Fig. 2. Mounted on a fixed stud shaft 53 at the under side of the bed plate is a bell-crank lever 54 having a roller stud 55 resting on the periphery of said cam 50. An arm of this lever extends above the bed plate through an opening therein and is connected through a link 56 with an arm 57 of the ring 45. During the operation of the machine in sewing on the fasteners, the roller on the lever 54 rides on the high part of the cam 50 and maintains the ring 45 in position with the pin 46 back out of the range of movement of the pawl 20, but when the feeding movement of the work-holder has been completed for the sewing stitches and the fastener is in position with the last eye in the path of the needle, a cut-out 58 in the cam will have reached a

position to permit the roller 55 on the lever to drop therein and cause the connected ring 45 to advance the pin 46 to its operative pawl-engaging position, such action of the parts being quickly effected by means of a coiled spring 60 which connects at one end with the upper arm of the lever 54 and at its opposite end with a fixed pin 61 on the bed plate. The cut-out 58 is of such length as to permit of the taking of the desired predetermined number of tacking stitches, following which the roller stud 55 will again be raised to the high part of the cam to withdraw the pin 46 to its inoperative position and so release the pawl 20 for actuating the work-holder in making the succeeding group or series of sewing-on stitches.

What I claim is:

1. In a machine of the class described, the combination with a work-holder, of means for operating the same to successively present different points of the supported work to the stitching mechanism, said means comprising co-operating pawl and ratchet members, and automatic means for rendering said pawl member ineffective to drive the ratchet member at a predetermined time prior to the stopping of the machine.

2. In a machine of the class described, the combination with a work-holder, of means for operating the same to successively present different points of the supported work to the stitching mechanism, said means comprising two co-operating members one acting to drive the other, a controller movable to and from an operative position for rendering said actuating member ineffective to drive the second member, and automatic means for shifting said controller to and from its operative position at predetermined times in the operation of the machine.

3. In a machine of the class described, the combination with a work-holder, of means for operating the same to successively present different points of the supported work to the stitching mechanism, said means comprising co-operating pawl and ratchet members, a controller movable to and from an operative position for rendering said pawl member ineffective to drive the ratchet member, and automatic means for shifting said controller to and from its operative position at predetermined times in the operation of the machine.

4. In a machine of the class described, the combination with a work-holder, of means for operating the same to successively present different points of the supported work to the stitching mechanism, said means comprising a rotatable ratchet member operatively connected with the work-holder, an oscillating member having a pawl mounted thereon for engaging with and driving the ratchet member, and a controller movable to and from position for rendering said pawl

ineffective at a predetermined time in the operation of the machine.

5. In a machine of the class described, the combination with a work-holder, of means for operating the same to successively present different points of the supported work to the stitching mechanism, said means comprising a rotatable ratchet member operatively connected with the work-holder, an oscillating member having a pawl mounted thereon for engaging with and driving the ratchet member, a controller movable to and from a position for rendering said pawl ineffective at a predetermined time in the operation of the machine, and an oscillatory carrier on which said controller is mounted.

6. In a machine of the class described, the combination with a work-holder, of means for operating the same to successively pre-

sent different points of the supported work to the stitching mechanism, said means comprising a rotatable ratchet member operatively connected with the work-holder, an oscillating member having a pawl mounted thereon for engaging with and driving the ratchet member, a controller movable to and from a position for rendering said pawl ineffective, an oscillatory carrier on which said controller is mounted, and means including a rotative cam for operating said oscillatory carrier at a predetermined time in the operation of the machine to shift the controller thereon into position for rendering the pawl ineffective.

In testimony whereof I affix my signature.

GEORGE W. NELSON.
